ROLLING MILL AND METHOD OF OPERATING THE SAME

Lorenz Iversen, Pittsburgh, Pa., assignor to Mesta Machine Company, Pittsburgh, Pa., a corporation of Pennsylvania

Application June 14, 1935, Serial No. 26,588

3 Claims. (Cl. 80—38)

This invention relates to rolling mills and the operation thereof and is herein particularly described as applied to a mill of the 4-high type for strip rolling. The rolling of strip, especially if it has a high ratio of width to thickness, entails the use of very high roll pressures and consequently the roll neck bearings are subject to extremely high unit loads. This fact has militated against the use of bearings of the lubricated journal type, and roller bearings have been employed to a considerable extent. There are numerous advantages in bearings of the lubricated journal type but they are open to the objection that when the mill is standing idle the pressure of the roll neck against the journal bearing squeezes out most of the film of lubricant. While it takes only a relatively short time to re-establish the film after the mill has started up, the wear attendant upon starting and re-establishing the film may be considerable, under extreme conditions the non-driven rolls may even refuse to turn, and variations in the thickness of the film may adversely affect the gauge of the product. The difficulty is particularly marked on the bottom roll of the mill because the weight of the roll is exerted downwardly and tends constantly to break the film of lubricant. The difficulty is not met in the bearings of the top roll because the top roll is thrust upwardly while it is working and, of course, it tends of its own weight to drop away from the upper part of the bearing shell and is restrained only by the lower part of the shell. In consequence there is no tendency to break the film at the point where it is most required for the top roll. Where mills of the backed-up type are used, the bearings of the bottom roll must carry the dead weight of the backing roll or rolls as well as the weight of the bottom work roll.

It is well recognized that a bearing of the lubricated journal type is subject to practically no wear so long as the oil film is maintained; but the problems peculiar to rolling mill practice have limited the applicability of bearings of this type. The present invention, by doing away with the principal cause for breakdown of the oil film, vastly enlarges the field of applicability of such bearings. I eliminate the tendency toward breaking down of the oil film due to weight of the rolls by balancing out the weight of the roll in large measure and particularly of the bottom roll. Roll balancing means, broadly speaking, are well known, but such roll balancing devices do not function to lessen the unit pressure on the bearings and minimize the tendency toward squeezing out or breaking down the oil film.

In the accompanying drawings illustrating certain preferred embodiments of the invention,

Figure 1 is a side elevation partly broken away showing a mill of the 4-high type having my invention applied thereto; 5

Figure 2 is a horizontal section to enlarged scale through the mill of Figure 1 taken on a plane tangent to the bottom of the bottom backing roll;

Figure 3 is a transverse vertical section showing the roll balancing mechanism in more detail; 10

Figure 4 is a section on the line IV—IV of Figure 3;

Figure 5 is a view corresponding to Figure 3 but showing a modified form of construction; 15

Figure 6 is a view corresponding to a portion of Figure 5 but to enlarged scale and partly broken away;

Figure 7 is a section on the line VII—VII of Figure 5; 20

Figure 8 is a view corresponding to Figure 3 but showing a still further modification; and

Figure 9 is a section on the line IX—IX of Figure 8.

The mill illustrated in Figures 1 to 4 inclusive 25 comprises housings 2 having windows 3 therein in which are mounted backing rolls 4 and 5 with intermediate work rolls 6 and 7. The backing rolls have necks working in chocks 8, the bearings being of the lubricated journal type. Suitable oil connections are indicated at 9. A highly satisfactory form which the bearing may take is more specifically described and claimed in my copending application Serial No. 727,701, filed May 26, 1934. The necks of the working rolls 6 30 and 7 are carried in chocks 10. The several chocks are all vertically slidable in the windows 3 of the housings. The spacing of the rolls during rolling is determined by the usual screw-down 40.

When the mill is standing idle the weight of the bottom rolls is borne by the lower bearings 8. In a modern mill this weight may be as much as 125,000 pounds. Such a load tends to squeeze the oil out of the bearings so that the oil film is ruptured or else will rupture immediately on starting up and before the rolls have rotated sufficiently to entrain a fresh supply of oil, carry it into the journal, and re-establish or renew the film. In order to reduce the load on the bearings of the lower roll, the roll is engaged externally of the journal surfaces and urged upwardly. In this form of the invention the balancing is accomplished by means of a thrust roller 12 running on bearings 13 mounted on a spindle 14. 50 55

The thrust roller 12 bears against the working face of the bottom roll 4 and extends over a substantial portion of its width. The surface of the roll 12 is highly finished and does not mar the hardened surface of the backing roll. It runs freely on its bearings so that there is no tendency to scratch even if any foreign particles should accidentally be entrained on the roll surfaces. Provision is made at 15 for lubricating the bearings 13. The spindle 14 is carried in a slide 16 which is movable vertically in a casing 17 supported between the housings 2. The casing 17 contains nested coil springs 18 which exert an upward force against the roll 4. This force is not sufficient to lift the weight of the bottom roll out of its bearings but is sufficient to reduce in great measure the pressure exerted on the oil film in the bottom journal bearings.

The springs act against the slide 16 through collars 19 and the collars slide on studs 20 having bottom flanges 21 which lie below the bottom ends of the springs. Heads 22 on the studs limit the expansion of the springs 18. This permits of initially compressing the springs 18 so that they are contained in a relatively small compass. The length to which the springs can expand is correspondingly limited and therefore the amount of upward movement of the rolls 12 is limited. It is not intended that this limit of movement shall be reached so long as the mill rolls are in place, but when it becomes necessary to change the mill rolls it is important that there be some such limit on the amount of upward movement of the roller 12.

Figures 5 to 7 illustrate a modified form of construction in which the roll 12a is carried in bearings on a spindle 14a, the spindle being urged upwardly by hydraulic plungers 30 working in cylinders 31. The cylinders 31 are formed in a casing 11a lying between the housings 2a and are connected through passages 32 to a conduit 33 which is connected to a controlled supply of fluid pressure. With this form of apparatus, the upward movement of the roller 12a is limited when a roll change is to be made by merely cutting off the fluid pressure.

Figures 8 and 9 show still another modification wherein the pressure roller 12b is mounted on a spindle 14b which, in turn, is carried by slides 40 movable up and down in a casing 17b supported between the housings 2b. The bottom of each slide 40 is engaged by one arm 41 of a lever pivoted at 42. The longer arms 43 of such levers are connected through links 44 to a counter-weight 45. The levers constitute a multiplying system whereby with a weight of reasonable size a considerable upward force can be exerted. In this case the upward movement of the roller 12b is limited by the engagement of faces 46 on the arms 41 of the levers with cooperating faces 47 on the housing 17b.

It is often necessary to redress the surfaces of the mill rolls and during the life of a roll there is a corresponding reduction in weight, which weight reduction is often considerable in amount. Preferably the upward force exerted by the balancing means is slightly less than the minimum weight of the roll, with due regard to dressing down of the roll body.

Where I have referred herein to bearings of

the "journal type" or of the "lubricated journal type", I have intended to refer to those bearings wherein the shaft has sliding as distinguished from rolling friction with its supporting surface, and I mean to include not only babbitt lined bearings but bearings of other material and construction, as, for example, water-lubricated bearings made of composition material.

While I have illustrated and described certain preferred embodiments of my invention, it is to be understood that the same is not limited thereto but may be otherwise embodied and practiced within the scope of the following claims.

I claim:

1. In the method of operating a rolling mill having rolls including a bottom roll with roll neck bearings of the lubricated journal type, the steps consisting in intermittently rotating the rolls and rolling material in the mill, resisting the rolling force transmitted through the bottom roll by means of the neck bearings, and, at least during those times when the bottom roll is not rotating, yieldingly applying to the body of the roll an upward force limited in amount to less than the dead weight of the bottom roll but equal to a substantial part of said weight, thereby substantially lessening the unit pressure in the bearings and limiting the extrusion of lubricant under such dead load, thus to insure the presence of a lubricant film in the bearings adequate to support the rolling load on resumption of rolling in the mill.

2. In the method of operating a rolling mill having rolls including a bottom roll with roll neck bearings of the lubricated journal type, the steps consisting in intermittently rotating the rolls and rolling material in the mill, resisting the rolling force transmitted through the bottom roll by means of the neck bearings, and, at least during those times when the bottom roll is not rotating, yieldingly applying to the body of the roll an upward force limited in amount to less than the dead weight of the bottom roll and the parts supported thereby but equal to a substantial part of said weight, thereby substantially lessening the unit pressure in the bearings and limiting the extrusion of lubricant under such dead load, thus to insure the presence of a lubricant film in the bearings adequate to support the rolling load on resumption of rolling in the mill.

3. In the method of operating a rolling mill having rolls including a bottom roll with roll neck bearings of the lubricated journal type, the steps consisting in intermittently rotating the rolls and rolling material in the mill, resisting the rolling force transmitted through the bottom roll by means of the neck bearings, engaging the body of the roll with a pressure roller and yieldingly applying to the body of the roll through said pressure roller an upward force limited in amount to less than the dead weight of the bottom roll but equal to a substantial part of said weight, thereby substantially lessening the unit pressure in the bearings and limiting the extrusion of lubricant under such dead load, thus to insure at all times the presence of a lubricant film in the bearings adequate to support the rolling load.
